UNITED STATES PATENT OFFICE.

LEE J. BLACK, OF BEAUMONT, TEXAS.

ROTARY WELL-DRILLING APPARATUS.

Application filed May 21, 1925. Serial No. 31,908.

To all whom it may concern:

Be it known that I, LEE J. BLACK, a citizen of the United States, residing at Beaumont, in the county of Jefferson and State of Texas, have invented certain new and useful Improvements in Rotary Well-Drilling Apparatus, of which the following is a specification.

This invention relates to rotary well drilling apparatus and more particularly to the construction of what is known as the drilling table of the rotary.

An important object of the invention is to produce a device of this character having a table formed in two sections and means whereby the two sections of the table may be either locked to one another and to the drive or one of the tables may be independently driven from the drive and the other table frictionally held against rotation so that when the rotation of the table is employed as a means for coupling two sections of drill pipe and the coupling between these sections is completed, the inner table may be moved against its frictional retainer and so prevents stripping of or damage to the threads of the coupling which, in the present type of rotary, is a common occurrence where the rotary is used as it almost invariably is in making of the coupling. With these present constructions, whether the coupling is damaged or not depends entirely upon the skill of the operator for if the operator fails to stop the rotation of the table when the coupling is properly made, the coupling is damaged either as to its threads or exterior so that it is materially weakened and cannot, with any degree of safety, be employed in a well. Often this damage to couplings necessitates the removal of not only the section of drill pipe which is being applied but likewise that section which has been attached to the drilling string and is partially lowered into the well. The disadvantage of this structure will immediately appear when it is pointed out that it is frequently necessary to withdraw the entire length of drill pipe in order that the drill bits employed at the lower end thereof may be sharpened or replaced.

A still further object of the invention is to produce a device of this character wherein the separation of the tables and accordingly the disconnection of the drill pipe from the drive may be effected while the rotary is

in operation and whereby this separation likewise effects the checking of motion of the drill pipe. In rotary drilling, circumstances frequently arise wherein an immediate disconnection of the drive is necessary or advisable. In the present structure, the control for this drive is located considerably to one side of the table and if the operator is closely attending the table, it is necessary for him to move a considerable distance before rotation of the table can be checked. While making this move, serious damage to the drilling mechanism may result.

A still further object of the invention is the provision of a readily produced structure of this character which will be no more complicated in its handling than the structures now employed and which occupies no greater space than the ordinary rotary drilling table.

These and other objects I attain by the construction shown in the accompanying drawings, wherein for the purpose of illustration is shown a preferred embodiment of my invention and wherein:

Figure 1 is a plan view of a drilling apparatus constructed in accordance with my invention;

Figure 2 is a view partially in section and partially in elevation of the apparatus showing the positions assumed by the parts when the device is employed for coupling sections of drill pipe;

Figure 3 is an enlarged view showing the outer table in section and a portion of the ring broken away, the ring being in the position in which the outer and inner tables are locked to one another;

Figure 4 is a similar view showing the position of the ring when the parts are unlocked and illustrating the fact that the brake is applied at this time; and

Figure 5 is a detailed view of the operating mechanism for the brake and ring elevating arm.

Figure 6 is a detail horizontal sectional view showing the connection between the table 20 and intermediate bushing 16;

Figure 7 is a detail horizontal sectional view showing the spline engagement between the locking ring and driving table.

Referring now more particularly to the drawings, the numeral 10 indicates the usual skids employed as a support for a base 11 and its extension 12, hereinafter to be

more particularly referred to. The base 11 has a central opening 13 and in accordance with my invention, about this opening a roller bearing track 14 is produced having 5 roller bearings 15 thereon. Seated upon the rollers 15 is what I term an intermediate bushing 16 which has a depending guiding flange 17 entering the central bore of the base 11.

10 This bushing has a central bore 18, the upper portion of which is conical, as indicated at 19, and provides a seat for a downwardly tapering inner table 20 which is provided with a central slip receiving 15 bore 21 having slips 22 arranged therein for engagement with a drill pipe 23 or with the drill stem (not herein disclosed). The upper portion of the intermediate bushing 16 and an overlying portion of the table 20 20 are formed with interlocking teeth 24 and 25, these teeth engaging when the central table is fully seated in the intermediate bushing to lock these two members to one another, as respects rotary motion. The 25 upper surface of the central table is formed with sockets 26, the purpose of which will hereinafter appear.

The upper surface of the intermediate bushing provides a roller track 27 with 30 which are engaged rollers 28 upon which is seated the inner lower face of an outer table 29. This outer table 29 has its upper surface substantially flush with the upper surface of the inner table 20 and the inner 35 table is preferably provided with a hook flange 30 engaging over an upstanding rib 31 formed upon the upper surface of the table 29 at the inner edge thereof. Formed in the under surface of the outer table 29 40 and partially overlying the upper surface of the intermediate bushing is an annular groove 32, the outer wall of which is provided with vertically extending notches forming teeth 33 which are slidably engaged 45 by similar teeth 34 formed upon the outer surface of a locking ring 35. This locking ring has at its upper end an inturned flange 36 overlying the upper outer surface of the intermediate bushing 16 and opposing faces 50 of this flange and the bushing are provided with teeth 37 and 38 which engage when the locking ring is lowered to a predetermined extent. When the teeth 37 and 38 are engaged, the intermediate bushing is locked to 55 the outer table 29 so that the tables 20, 29, and the intermediate bushing 16 rotate as a unit. The upper surface of the table 29 has circumferentially spaced sockets 39, the purpose of which will presently appear.

60 As regards its remaining structure, the outer table 29 resembles the tables now in use upon rotary well drilling apparatus having formed upon its under outer edge gear teeth 40 for engagement by a drive pinion

41 secured to a shaft 42 mounted in bearings 65 43 carried by the base extension 12. The under surface of the table is further formed with the usual depending portion 44 having at its lower end an outstanding outwardly directed horizontal flange 45 for engagement 70 by hold-down blocks 46 carried by the base 11.

Extending about the outer surface of the intermediate bushing within a groove 47 formed therein is a friction brake band 48, 75 one end of which is adjustably connected, as at 49, to a standard 50 arising from the base 11. To the opposite end of this band is connected a crank arm 51 of a rock shaft 52 mounted for rocking movement in the 80 base 11 and having beneath the base a second arm 53. The skids 10 are connected by a cross brace 54 upon which in alignment with the free end of the arm 53, a cylinder 55 is secured. Upon the rod 56 of the piston 85 of this cylinder a cross head 57 is connected by a link 58 with the free end of the arm 53. This rod 56 preferably extends from the opposite end of the cylinder 55 and is there connected with the lower end of a 90 suitably pivoted lever 59 by means of which the rod may be shifted without the use of fluid pressure. Ordinarily movement of the rod will be controlled by fluid pressure and a suitable valve of any usual construction and not herein disclosed for the reason that it forms no part of my invention.

Pivottally engaged with the base at diametrically opposing points as regards the tables 20, 29, and upon a diameter at right 100 angles to that upon which the free end of the arm 53 is located are a pair of levers 60 pivoted intermediate their ends upon the base 11, the upper ends of these levers having rollers 61 for engagement with the under 105 surface of the lower and the outwardly directed flange 35 of the locking ring. The lower ends of these levers are connected by a U-shaped yoke 62 with the rod 56, the rod being loosely directed through the yoke and 110 having a spring 63, one end of which engages the yoke and the opposite end of which engages the adjacent end of the cross head 57.

In the operation of the device, it will be 115 obvious that if the rod 56 be shifted in the direction of the arrow of Figure 5, the result will be that the rollers 61 of the levers 60 will be brought into engagement with the locking ring and this locking ring elevated 120 and at the same time, this rod through the arm 53 will constrict the brake band 48 upon the intermediate bushing 16, checking the rotation thereof. Since the elevation of the locking rings frees the intermediate bushing, the table 29 will now rotate alone. When the rod is moved in the opposite direction, the brake band will be loosened and 125

at the same time, the locking ring will be lowered and will lock together the outer table 29 and the intermediate bushing so that both tables 20 and 29 are rotating. When it is

- 5 desired to employ the device for coupling pipe, the position and operation first described is employed, that is to say, the outer table is driven from the shaft 42 while the inner table is held against rotation by the 10 friction band. Before rotation is started, posts 64 and 65 are entered in the sockets 26 and 39 respectively. Against the post 64 is engaged the handle of a wrench 66 which is employed for holding the lower pipe section 15 23 against rotation. Against the post 65 is engaged the handle of a second wrench 67 which engages the upper pipe section 23', for the purpose of rotating the same to cause the coupling of these sections. The outer 20 table is now thrown into rotation and this rotation may be continued until the coupling is entirely completed at which time the drag transmitted to the inner table and through the posts 64, 65 and wrenches 66 and 67 will 25 be in turn transmitted to the intermediate bushing 16 thereof and this intermediate bushing caused to rotate against the action of its friction band so that no damage will result to the threads of the coupling. It will, 30 of course, be obvious that during drilling operations if, at any time, it is desired to temporarily disconnect the drilling string from the drive, this may be accomplished by operating the rod 56 and not only will a 35 disconnection be effected but the inner table will be braked against rotation.

Since the structure hereinbefore set forth is obviously but one preferred example of my invention, I do not wish to be understood 40 as limiting myself to the specific structure thereof except as hereinafter claimed.

I claim:—

1. In a well drilling machine and in combination a base, a member rotatable upon the base having means associated therewith for supporting a drill pipe and securing the same against rotation with relation to the member, a table concentric with the member, means for rotating the table and means operable during rotation of the table for locking the table and said member against relative rotation and operating means for said locking means stationary with relation to said table.
- 55 2. In a well drilling machine and in combination a base, a member rotatable upon the base having means associated therewith for supporting a drill pipe and securing the same against rotation with relation to the member, a table concentric with the member, means for rotating the table, locking means operable during rotation of the table for locking the table and said member against relative rotation comprising a ring splined to said table and having clutch teeth, clutch teeth upon said member with which the clutch teeth of the locking ring engage in one position of the locking ring, means for shifting said ring to inoperative position comprising a plurality of levers having rollers engaging the ring at circumferentially spaced points and means for simulta-

65 splined to said table and having clutch teeth and clutch teeth upon said member with which the clutch teeth of the locking ring engage in one position of the locking ring.

3. In a well drilling machine and in combination a base, a member rotatable upon the base having means associated therewith for supporting a drill pipe and securing the same against rotation with relation to the member, a table concentric with the member, means for rotating the table and locking means operable during rotation of the table for locking the table and said member against relative rotation and means operable to brake rotation of the member until a predetermined pressure is applied thereto to 80 rotate the same.

4. In a well drilling machine and in combination a base, a member rotatable upon the base having means associated therewith for supporting a drill pipe and securing the same against rotation with relation to the member, a table concentric with the member, means for rotating the table, locking means operable during rotation of the table for locking the table and said member against relative rotation, means operable to brake rotation of the member until a predetermined pressure is applied thereto to 85 rotate the same and means for simultaneously applying the braking means and releasing said locking means.

5. In a well drilling machine and in combination a base, a member rotatable upon the base having means associated therewith for supporting a drill pipe and securing the same against rotation with relation to the member, a table concentric with the member, means for rotating the table, locking means operable during rotation of the table for locking the table and said member against 90 relative rotation, means operable to brake rotation of the member until a predetermined pressure is applied thereto to rotate the same and wrench posts removably supported from said table and said member.

6. In a well drilling machine and in combination a base, a member rotatable upon the base having means associated therewith for supporting a drill pipe and securing the same against rotation with relation to the member, a table concentric with the member, means for rotating the table, locking means operable during rotation of the table for locking the table and said member against relative rotation comprising a ring 100 splined to said table and having clutch teeth, clutch teeth upon said member with which the clutch teeth of the locking ring engage in one position of the locking ring, means for shifting said ring to inoperative position comprising a plurality of levers having 105 rollers engaging the ring at circumferentially spaced points and means for simulta-

neously shifting the levers, said ring having the teeth thereof normally engaged with the teeth of the member.

7. In a well drilling machine and in combination a base, a member rotatable upon the base having means associated therewith for supporting a drill pipe and securing the same against rotation with relation to the member, a table concentric with the member, means for rotating the table, locking means operable during rotation of the table for locking the table and said member against relative rotation comprising a ring splined to said table and having clutch teeth, clutch teeth upon said member with which the clutch teeth of the locking ring engage in one position of the locking ring, means for shifting said ring to inoperative position comprising a plurality of levers having rollers engaging the ring at circumferentially spaced points, means for simultaneously shifting the levers, said ring having the teeth thereof normally engaged with the teeth of the member, a brake band associated with said member and means for tightening the brake band upon the member as the levers are operated to shift said ring to inoperative position.

8. In a well drilling machine and in combination a base, a member rotatable upon the base having means associated therewith for supporting a drill pipe and securing the same against rotation with relation to the member, a table concentric with the member, means for rotating the table, locking means operable during rotation of the table for locking the table and said member against relative rotation comprising a ring splined to said table and having clutch teeth, clutch teeth upon said member with which the clutch teeth of the locking ring engage in one position of the locking ring, means for shifting said ring to inoperative position comprising a plurality of levers having rollers engaging the ring at circumferentially spaced points, means for simultaneously shifting the levers, said ring having the teeth thereof normally engaged with the teeth of the member, a brake band associated with said member, means for tightening the brake band upon the member as the levers are operated to shift said ring to inoperative position comprising a cylinder, a piston therein, a rod for the piston, a connection between the rod and one end of the brake band and a connection between the rod and the connection between said levers.

9. In a well drilling machine and in combination a base, a member rotatable upon the base having means associated therewith for supporting a drill pipe and securing the same against rotation with relation to the member, a table concentric with the member, means for rotating the table, locking means operable during rotation of the table for

locking the table and said member against relative rotation comprising a ring splined to said table and having clutch teeth, clutch teeth upon said member with which the clutch teeth of the locking ring engage in one position of the locking ring, means for shifting said ring to inoperative position comprising a plurality of levers having rollers engaging the ring at circumferentially spaced points, means for simultaneously shifting the levers, said ring having the teeth thereof normally engaged with the teeth of the member, a brake band associated with said member and means for tightening the brake band upon the member as the levers are operated to shift said ring to inoperative position comprising a cylinder, a piston therein, a rod for the piston, a connection between the rod and one end of the brake band, a connection between the rod and the connection between said levers, and means for manually shifting said rod.

10. In a well drilling machine and in combination a base, a member rotatable upon the base having means associated therewith for supporting a drill pipe and securing the same against rotation with relation to the member, a table concentric with the member, means for rotating the table, locking means operable during rotation of the table for locking the table and said member against relative rotation, a brake band surrounding said member and having one end thereof adjustably secured to said base and means for shifting the opposite end of the brake band to cause the band to engage or release said member.

11. In a well drilling machine and in combination a base, a member rotatable upon the base having means associated therewith for supporting a drill pipe and securing the same against rotation with relation to the member, a table concentric with the member, means for rotating the table, locking means operable during rotation of the table for locking the table and said member against relative rotation, a brake band surrounding said member and having one end thereof adjustably secured to said base and means for shifting the opposite end of the brake band to cause the band to engage or release said member and for simultaneously rendering the locking means inoperative.

12. In a well drilling machine and in combination a base, an intermediate bushing rotatable upon the base and having a bore, a table insertable in said bore and when inserted having teeth engaging the teeth formed upon said intermediate bushing whereby the intermediate bushing and table are locked against rotation with relation to one another, said table having a central bore affording slip seats, means for braking the intermediate bushing, a rotatable element concentric with the intermediate bushing

and means for locking the rotatable element and intermediate bushing to one another for simultaneous rotation.

13. In a well drilling machine and in combination a base, an intermediate bushing rotatable upon the base and having a bore, a table insertable in said bore and when inserted having teeth engaging the teeth formed upon said intermediate bushing whereby the intermediate bushing and table are locked against rotation with relation to one another, said table having a central bore affording slip seats, means for braking the intermediate bushing, a rotatable element concentric with the intermediate bushing, the rotatable element being rotatably mounted upon the intermediate bushing and having splined thereto a ring having teeth, the intermediate bushing having teeth for coaction with the teeth of the ring and means for shifting the ring to engage or disengage the teeth during rotation of the rotatable element.

14. In a well drilling machine and in combination a base, an intermediate bushing rotatable upon the base and having a bore, a table insertable in said bore and when inserted having teeth engaging the teeth formed upon said intermediate bushing whereby the intermediate bushing and table are locked against rotation with relation to one another, said table having a central bore affording slip seats, means for braking the intermediate bushing, a rotatable element concentric with the intermediate bushing, the rotatable element being rotatably mounted upon the intermediate bushing and having splined thereto a ring having teeth, the intermediate bushing having teeth for coaction with the teeth of the ring, means for shifting the ring to engage or disengage the teeth during rotation of the rotatable element comprising a plurality of levers having rollers engaging the ring at circumferentially spaced points and means for simultaneously shifting the levers.

15. In a well drilling machine and in combination a base, an intermediate bushing rotatable upon the base and having a bore, a table insertable in said bore and when inserted having teeth engaging the teeth formed upon said intermediate bushing whereby the intermediate bushing and table are locked against rotation with relation to one another, said table having a central bore affording slip seats, means for braking the intermediate bushing, a rotatable element concentric with the intermediate bushing, the rotatable element being rotatably mounted upon the intermediate bushing and having splined thereto a ring having teeth, the intermediate bushing having teeth for coaction with the teeth of the ring, means for shifting the ring to engage or disengage the teeth during rotation of the rotatable element

comprising a plurality of levers having rollers engaging the ring at circumferentially spaced points, means for simultaneously shifting the levers, a brake for the intermediate bushing and a connection between the last named means and the brake whereby the brake is applied as the ring is shifted to disengage said teeth.

16. In a well drilling machine and in combination, a base, a member rotatable upon the base having associated therewith means supporting a drill pipe and securing the same against rotation with relation to the member, a table concentric with and rotatably supported by the member, means for rotating the table and locking means shiftable axially of said table and member for locking the table and member against relative rotation and means for shifting said locking means during rotation of the table.

17. In a well drilling machine and in combination a base, a member rotatable upon the base having associated therewith means supporting a drill pipe and securing the same against rotation with relation to the member, a table concentric with and rotatably supported by the member, means for rotating the table, locking means shiftable axially of said table and member for locking the table and member against relative rotation, means for shifting said locking means during rotation of the table, the under surface of the table having an annular groove one wall of which is provided with vertically extending teeth, said locking means comprising a ring having teeth engaging the teeth of the table and other teeth confronting said member, the member having teeth for engagement by the last named teeth of the ring when in one position.

18. In a well drilling machine and in combination a base, a member rotatable upon the base having associated therewith means supporting a drill pipe and securing the same against rotation with relation to the member, a table concentric with and rotatably supported by the member, means for rotating the table, locking means shiftable axially of said table and member for locking the table and member against relative rotation, means for shifting said locking means during rotation of the table, the under surface of the table having an annular groove one wall of which is provided with vertically extending teeth, said locking means comprising a ring having teeth engaging the teeth of the table, other teeth confronting said member, the member having teeth for engagement by the last named teeth of the ring when in one position, said shifting means comprising levers pivoted upon said base and having rollers engaging the ring and means for simultaneously shifting the levers.

19. In a well drilling machine and in com-

- bination a base, a member rotatable upon the base having means associated therewith for supporting a drill pipe and securing the same against rotation with relation to the member, a table concentric with the member, means for rotating the table and means operable to brake rotation of the member until a predetermined pressure is applied thereto to rotate the same.
- 10 20. In a well drilling machine and in combination a base, a member rotatable upon the base having means associated therewith for supporting a drill pipe and securing the same against rotation with relation to the member, a drive including a table concentric with the member, means for clutching and unclutching the drive to the member, a brake for the member and means for simultane-

ously applying the brake and connecting the clutch.

21. In a well drilling machine and in combination a base, a member rotatable upon the base having means associated therewith for supporting a drill pipe and securing the same against rotation with relation to the member, a drive including a table concentric with the member, means for clutching and unclutching the drive to the member, a brake for the member and means for simultaneously applying the brake and connecting the clutch operable during operation of the drive and stationary with relation to the table.

In testimony whereof I affix my signature.

LEE J. BLACK.
